His Attorney.

UNITED STATES PATENT OFFICE

FRIEDRICH SASS, OF BERLIN-CHARLOTTENBURG, GERMANY, ASSIGNOR TO GENERAL ELECTRIC COMPANY, A CORPORATION OF NEW YORK

INTERNAL COMBUSTION ENGINE

Application filed May 27, 1929, Serial No. 366,136, and in Germany June 21, 1928.

This invention relates to fuel injectors for internal combustion engines and particularly to fuel injectors for use with double acting engines having what is usually termed solid injection, although it is not necessarily limited thereto. It will be understood that by solid injection is meant a feed for engines wherein the fuel is forced by pressure through the nozzles into the cylinder without the use of blast air, the nozzles serving to atomize the fuel charge.

In internal combustion engines employing solid injection means it is desirable, in order to obtain a complete mixture of fuel and air in the cylinder necessary for good combustion, that the fuel is fed into the cylinder evenly through a proper number of nozzles. In the closed end of a double-acting engine this can be accomplished by a centrally arranged fuel valve having a proper number of nozzles. At the other end of the cylinder, however, the piston rod renders such an arrangement impossible. It is especially important on account of the reduced volume and the annular shape of the combustion chamber that a proper distribution of the fuel is obtained.

According to my invention I provide a common fuel valve for feeding fuel charges through distributing means and a plurality of nozzles into the cylinder.

In the drawing Fig. 1 is a view partly in elevation and partly in section of one embodiment of my invention applied to a cylinder. Fig. 2 is a sectional view taken on line 2-2 of Fig. 1.

Referring to the drawing 5 indicates the base of an engine, 6, the cylinder thereof closed at its lower end by a cylinder head 7, and 8 a piston rod passing through said head.

According to my invention I provide a desired number of atomizing nozzles 10 which may be concentrically disposed around the piston rod in spaced relation thereto and project through the cylinder head 7 into the interior of cylinder 6. Pipes 11 connected to the outer ends of nozzles 10 support and communicate with the chamber of an annular fuel manifold 12 which surrounds and is spaced from the piston rod 8. But one dis-

tributor is illustrated though several may be provided. The fuel fed to the fuel manifold 12 is controlled by a fuel valve 13 supported in close proximity to said fuel manifold by the frame 1 or by the distributor 55 itself. The connection pipes 11 and 14 are made as short as possible in order to insure even distribution and even flow of the fuel charges through the pipes, distributor and nozzles. The pipes 11 are made just long 60 enough to accommodate connection means so that the nozzles and the manifold may be cleaned or replaced. Pipes 14 are also adapted to be readily connected and disconnected.

In the above arrangement the common fuel valve controls the pressure of the fuel charge to the manifold or manifolds and insures a uniform pressure in said last named unit or units. With a uniform pressure in the manifold the flow of fuel through each nozzle is 70 controlled by the size of the opening in its atomizer tip. By making the tip openings of the same diameter, equal amounts of fuel will be forced into the cylinder by each nozzle. The number of nozzles employed is 75 dependent on the size of the cylinder. By properly spacing the nozzles a uniform distribution of the fuel charge in the cylinder is obtained in both the annular shaped space of the piston rod end and the cylindrical shaped 80 closed end of the cylinder.

I have shown my invention applied to the lower end of a single cylinder engine but it may be applied to either the upper or lower end of the cylinder and in single or multiple 85 cylinder engines.

In accordance with the provisions of the patent statutes, I have shown the principle of operation of my invention, together with the apparatus which I now consider to represent the best embodiment thereof, but I desire to have it understood that the apparatus shown is only illustrative and that the invention may be carried out by other means.

What I claim as new and desire to secure 95 by Letters Patent of the United States is:

1. The combination with an engine cylinder having a piston rod passing through one head of said cylinder, of a plurality of atomizing nozzles for solid injection fixed in said head, 100

an annular shaped fuel manifold surrounding said piston rod, conduits connecting said nozzles in parallel to said fuel manifold, and a fuel valve for controlling the flow of fuel to said fuel manifold.

5. 2. In a fuel distribution system for an engine, employing solid injection, the combination of a cylinder, a piston rod passing through one head of said cylinder, a plurality

10 of atomizing nozzles fixed in said head, an annular shaped fuel manifold disposed adjacent the nozzles and around said piston rod, conduits connecting said nozzles in parallel to said fuel manifold, and a fuel valve mounted in close proximity to said fuel manifold and connected therewith for controlling the flow of fuel to said fuel manifold, whereby all of said nozzles receive fuel simultaneously from the manifold.

15 20. In witness whereof, I have hereunto set my hand this 13th day of May, 1929.

FRIEDRICH SASS.
